ABSTRACT OF THE DISCLOSURE

A continuous form envelope assembly comprised of superimposed plies defining fronts and backs of sealed envelopes delimited by spaced glue lines and transverse lines of weakening for separating the individual envelope units from the assembly, wherein each envelope of the completed assembly is provided with an opening in a marginal edge to facilitate subsequent insertion of additional material, and means in the form of an adhesive line for sealing the opening.

BACKGROUND OF THE INVENTION

Field of the invention

This invention relates to continuous form envelope assemblies and more particularly to an envelope assembly which is provided with envelope front and back sheets and insert materials and with a means for inserting additional material to the interior of the envelope subsequent to the assembly thereof but prior to sending the same to a recipient, which means is closable prior to so sending the envelope to a recipient.

Description of the prior art

Pertinent prior art in this field includes my issued Patent No. 3,104,799, entitled "Envelope Assembly." This patent discloses a continuous envelope assembly wherein insert material is captivated between envelope front and back plies in one margin and access may be gained to the interior of the envelope and the insert material placed in a condition for extraction by removing one margin of the envelope along a line of weakening. The entire assembly may be pre-printed with non-variable information, such as return address, fixed information on the insert sheet, and a mailing permit. After assembly, further printing in the form of variable information, such as a recipient's address and an amount owing or amount due each recipient may be printed on the exterior of the envelopes as well as to the interior thereof with the aid of spot carbons, or the like. Then each envelope may be separated from the assembly along transverse lines of 50 weakening and mailed to the recipient.

Summary of the invention

The present invention is, in brief, an improvement in the aforementioned Patent No. 3,104,799 in that it is directed to the provision of a means in the assembly for adding additional material to each envelope of the assembly at a time and point remote from the initial assembly thereof. Furthermore, each envelope may then be completely sealed after the insertion of the additional material prior to mailing to a recipient.

An example of an ideal application for this invention is in the field of monthly bank statements. The pre-assembled insert material, which is in the initial envelope assembly, may be a monthly statement which is calculated on a business machine which also addresses the envelopes. Spot carbons in the interior of the envelope transfer the pertinent information to the insert material. The cancelled checks may be subsequently inserted into each envelope, the envelope sealed, and then sent to a recipient.

It is a primary object of this invention to provide an improved continuous envelope assembly.

2

It is another object of this invention to provide an improved continuous envelope assembly having means for inserting additional material into the assembly at a point remote in time and place from the initial assembly but prior to mailing the envelope to a recipient.

Another object of this invention is to provide a continuous form envelope assembly which as initially assembled is provided with means for adding supplementary insert material and sealing the enclosure prior to mailing the envelope to a recipient.

Other objects and advantages will be readily apparent from the following detailed description taken in connection with the accompanying drawings, in which:

Brief description of the drawings

FIGURE 1 is a fragmentary, broken, top plan view partially broken away in section, of a portion of the envelope assembly of this invention;

FIGURE 2 is an exploded section view, taken generally along the line 2—2 of FIGURE 1;

FIGURE 3 is a perspective view of an individual envelope from the completed assembly, showing supplementary insert material being inserted into the envelope, one corner of the envelope being turned back for clarity of illustration;

FIGURE 4 is a fragmentary perspective view of one marginal edge of the envelope after the supplementary insert material has been inserted into the envelope and the one open edge sealed;

FIGURE 5 is a fragmentary sectional view taken generally along the line 5—5 of FIGURE 4;

FIGURE 6 is a fragmentary top plan view, partially broken away in section, of an alternate form of the invention;

FIGURE 7 is a top plan view of an individual envelope separated from the assembly shown in FIGURE 6, with portions turned back for clarity of illustration, and showing an item of supplementary insert material about to be inserted into the envelope; and

FIGURE 8 is an exploded section view, taken generally along the line 8—8 of FIGURE 7.

Description of the preferred embodiments

Envelope assembly 10, as shown in FIGURES 1 and 2, includes an overlying master or record ply 12, a sheet of transfer material, such as carbon paper and the like 14, a continuous envelope front stationery strip 16, which may have standard indicia such as a mailing permit 16', pre-printed thereon, an insert sheet 18, which may, as illustrated, be in continuous strip form and suitably die-cut at spaced points 18', and an envelope back sheet 20. Generally the nature of the assembly is similar to that shown in my Patent No. 3,104,799. The record ply 12 may be separated from the assembly and retained for office use, and carbon ply 14 may be discarded. Certain non-variable information in addition to the pre-printed indicia 16' (such as a customer's name and address and an amount owing) may be subsequently printed on the envelope assembly and in the insert ply by business machines with the aid of spot carbons or the like in the interior of the assembly as shown and described in the aforementioned Patent 3,104,799.

Control punch holes 22 are provided in one margin, such as margins 12a, 14a, 16a, 18a and 20a of the several plies 12, 14, 16, 18 and 20, respectively, as well as in the opposite margins 12b, 14b and 16b of plies 12, 14 and 16, to assist in feeding the assembly and maintaining the same in registration during assembly and pre-printing thereof. Longitudinally extending glue lines 24a and 24b adhere plies 16, 18 and 20 together inside the marginal edges 16a, 18a and 20a. In addition, spaced transversely extending glue lines 26 adhere plies 16 and 20 together between

the die-cut 18' of insert ply 18 to thereby define individual envelope pockets 27. Longitudinally spaced transverse lines of weakening 28 throughout the assembly divide the assembly into individual envelope units 30 which may be separated from the assembly along the lines of weakening 28.

After assembly and prior to separation of the individual units 30 from the assembly, plies 12 and 14 may be removed and margins 16a, 18a, 20a, and 16b separated along trim lines 32 and 34. The assembly, particularly plies 16, 18 and 20, is provided with a perforation line 36 which is interiorly of glue lines 24a and 24b, defining a tear-off strip 36a, so that access may be gained to the interior of the resultant envelope and the insert material placed in a condition for extraction therefrom by merely separating tear strip 36a along line 36.

Means is further provided for gaining access to the individual envelope units after completion of the assembly for adding supplementary insert material, prior to sending the envelope to a recipient.

As can be best seen in FIGURES 1 and 2, the envelope ply 16 is wider than the remaining envelope plies, such as insert ply 18 and envelope back 20. That portion of front ply 16 which extends beyond the lower plies includes a fold line 38 thereby defining an integral flap portion 40. The underside of flap 40 includes a line of adhesive, such as a remoistenable glue 42 so that the flap and its glue provide a means for sealing the envelope after the insertion of supplementary insert material.

After the envelope assembly has been pre-printed and assembled, printed with variable information for each envelope unit, then separated into individual envelopes 30, each envelope is ready for the addition of supplementary insert material. As best seen in FIGURES 3 through 5, this is accomplished by thrusting the insert material 43 through the normally open means for gaining access to the envelope or open marginal end 44 of the envelope where the flap 40 is found.

After the supplementary insert material is inside of the envelope 30, flap 40 may be folded about fold line 38 and glue line 42 moistened to adhere the flap to the back ply 20 and enclose the open end 44. The envelope is now in a condition for mailing to a recipient who, upon receipt of the same, may separate tear strip 36a along line 36, thereby gaining access to the interior of the envelope and placing insert ply 18, as well as insert material 43, in a condition for extraction from the interior of the assembly.

In FIGURES 6 through 8, an alternate embodiment is shown. Here envelope assembly 110 also includes a top master ply 112 which may be retained for office use, a sheet of transfer material (not shown), envelope front ply 116 which contains certain pre-printed indicia, such as a mailing permit 116', an envelope insert ply 118 which may be in strip form and suitably die-cut at spaced areas, such as 118', and an envelope back ply 120. Control punch holes 122 are provided in the margins 112a, 116a, 118a and 120a, as well as in margins 112b, 116b and 120b to assist in feeding the assembly through suitable printing and assembly mechanism and the like.

Longitudinally extending glue line 124a and spaced longitudinally extending glue line 124b extend lengthwise of the assembly securing plies 116, 118 and 120, together interiorly of margins 116a, 118a and 120a and securing plies 116 and 120 together interiorly of the opposite margin 116b and 120b. Longitudinally spaced, transverse glue lines 126 secure front and back plies 116 and 120 together in the space between die-cuts 118' in areas defining one edge of the envelope which, in the illustrated embodiment, is the bottom edge thereby combining with glue lines 124a and 124b to provide an envelope pocket 127. Transverse lines of weakening 128 provide a means for separating individual envelope units 130 from the assembly, which units are secured together along glue lines 124a, 124b and 126.

Margins 112a, 116a, 118a, 120a may be separated along trim line 132 and margins 112b, 116b, and 120b

5 may be separated along trim line 134 prior to removing
10 ply 112 and separating the individual envelope units 130 from the assembly. Perforation line 136 extends inside
15 glue line 124a, defining a tear-off strip 136a. Access may
20 be gained to the interior of each envelope 130 and the
25 insert material 118 placed in a condition for extraction
30 by merely separating tear-off strip 136a along perforation
35 line 136.

The alternate embodiment is also provided with means
40 for gaining access to the interior of the individual envelope
45 units after completion of the assembly for adding
supplementary insert material, prior to sending the envelope
50 to a recipient. One of the piles (back ply 120 in
the illustrated embodiment) is die-cut at laterally spaced
55 areas 138a, 138b for a small distance inwardly from one
marginal edge of each envelope unit. In the illustrated
60 embodiment, this die-cut extends inwardly from that edge
which would, in the resultant envelope unit, be the top
65 edge thereof. These two die-cuts define a flap portion
70 140 which is provided with an adhesive in the form of a
75 remoistenable glue line 142. Thus, when the envelopes
80 130 are separated from the assembly, each has an open
85 end 143 through which supplementary insert material 144
90 may be inserted into the envelope pocket 127. After the
95 supplementary insert material is positioned within the envelope,
100 the remoistenable glue line 142 may be activated by
105 moisture and placed in a condition for adhering contact
110 with the underside of the opposite or front ply 116
115 to completely seal the interior of the envelope with the
120 supplemental insert material therein. As was the case with
125 envelope 30, the recipient may gain access to the interior
130 of the envelope and place the insert material 114 and sup-
135 plementary insert material 144 in a condition for extraction
140 by merely removing the tear-off strip 136a along per-
145 foration line 136.

150 The foregoing detailed description has been given for
155 clearness of understanding only, and no limitations should
160 be understood therefrom, as some modifications may be
165 obvious to those skilled in the art.

I claim:

1. An assembly of stuffed sealed envelopes, comprising:
170 superimposed plies defining fronts and backs of sealed envelopes; insert material between said front and back plies;
175 means connecting the front and back plies together in spaced areas defining individual envelope pockets; spaced lines of weakening in the plies defining individual envelope units separable from the assembly; and
180 normally open means for gaining access to the interior of individual envelope units after completion of the assembly for adding supplementary insert material to the individual envelope pockets at a time and point remote from the initial assembly thereof, including means integral with one of the front and back plies for subsequently closing the means for gaining access to the interior of the envelope.

2. The envelope assembly of claim 1 wherein one of the front and back plies is provided with an integral flap along one free edge, said flap being provided with adhering means so that after the supplementary insert material is added to the envelope unit, the flap and adhering means may sealingly engage the opposite envelope ply to complete the enclosure.

3. The envelope assembly of claim 2 wherein the normally open means for gaining access to the interior of the envelopes includes a die-cut area in one of the front and back plies extending inwardly from one edge of the one ply thereby defining a flap portion, and wherein said flap portion is free from engagement with its opposite ply during initial assembly of the envelope.

4. The envelope assembly of claim 2 wherein the flap comprises an integral extension of one of the front and back plies which may be folded over and adhered to the other ply after the supplementary insert material has been added to the interior of the envelope to completely enclose the envelope unit.

5. An assembly of stuffed sealed envelopes, comprising superimposed plies defining fronts and backs of sealed envelopes; insert material between said front and back plies; spaced lines of weakening in the plies defining individual envelope units separable from the assembly; means connecting the front and back plies together to define individual envelope pockets with at least a portion of one edge of the front and back plies of each envelope unit free from connection to each other; and means along and integral with said one unconnected edge portion for closing the unconnected portion at a time and point removed from the initial assembly of the envelope unit.

6. The envelope assembly of claim 5 wherein the insert material is connected to the envelope front and back along at least a portion of one marginal edge of the assembly and wherein the remaining marginal areas of the front and back plies includes the unconnected portion thereof.

7. The envelope assembly of claim 6 wherein the means for closing the unconnected portion is constructed and arranged to engage the front and back plies free of engagement with the insert material.

8. The envelope assembly of claim 7 wherein the unconnected portion includes a hinged flap formed in one of the front and back plies and the means for closing the unconnected portion includes an adhesive positioned

on the flap to sealingly engage the other of the front and back plies.

9. The envelope assembly of claim 8 wherein the flap is defined by spaced die cuts extending inwardly from a marginal edge of said one ply, and the insert material has a marginal edge which is inset relative to the one ply marginal edge wherein a flap is provided so that adhesive on the flap will engage only the other ply.

10. The envelope assembly of claim 8 wherein the flap comprises a marginal extension of the one ply relative to the other with adhesive on the flap so that the unconnected portion of the front and back plies may be closed by folding the flap over into facial engagement with the other ply.
